FARM BOAT

William W. Johnson, Des Moines, Iowa

Application June 7, 1932. Serial No. 615,881

5 Claims. (Cl. 280—144)

The object of this invention is to provide an improved construction for a farm boat or sled which is especially designed for convenience in transporting loads of different kinds, either loose or in a wagon box.

A further object of the invention is to provide an improved construction for a farm boat or sled having bolsters which are removable and replaceable, and also having standards which are pivotally and removably mounted on the bolsters and provided with pivotally secured braces adapted to engage in sockets in the bolster when the standards are in upright position.

Still another object is to provide an improved farm boat or sled adapted for supporting farm machinery and the like and including means arranged longitudinally of its side margins to support the discs of a harrow in such manner as to prevent the discs from cutting or injuring the platform of the boat.

With these and other objects in view my invention consists in the construction, arrangement and combination of the various parts of my device, whereby the objects contemplated are attained, as hereinafter more fully set forth, pointed out in my claims, and illustrated in the accompanying drawings, in which:—

Figure 1 is a plan view of a boat or sled involving my invention.

Figure 2 is a side elevation of the same.

Figure 3 is a longitudinal section centrally of the device on the line 3—3 of Figure 1.

Figure 4 is an enlarged cross section on the line 4—4 of Figure 1.

Figure 5 is a detail section on the line 5—5 of Figure 1.

Figure 6 is a detail cross section of one side marginal portion of the device illustrating particularly the means for supporting a disc harrow to prevent injury to the platform or deck.

This invention has to do with boats or sleds such as are commonly used on farms and sometimes for industrial purposes for transporting heavy loads such as logs, lumber, machinery and the like. It includes convenient means, namely removable bolsters having removable standards, for retaining a wagon box or for loads such as logs or lumber.

The device includes a pair of spaced parallel runners 10, each provided with a suitable shoe 12 on its lower margin. The runners support a platform or deck 14 which may conveniently be formed of transversely arranged timbers or bars. The boat or sled may be provided with a clevis 16 at its forward end to receive a tongue or other

draft means and may also be provided with a clevis 18 at its rear end for the purpose of attaching a follower or trailer device thereto.

The device also includes a pair of transversely arranged bolsters 20 suitably spaced apart and 60 these bolsters are removably and replaceably mounted on the platform 14, preferably by means of pins 22 extending through openings in the bolsters and into aligned recesses 24 in the deck. The heads of the pins 22 preferably are countersunk in the upper surfaces of the bolsters. Cleats 26 are arranged transversely of and fixed to the bolsters in any suitable manner. The cleats are countersunk in the lower surfaces of the bolsters and project in both directions therefrom to assist in preventing rocking movement of the bolsters. The pins 22 may be withdrawn from the recesses 24 when it is desired to remove the bolsters from the sled.

At each end portion of each of the bolsters 20 75 a metal plate 28 is mounted on and countersunk in the upper surface of the bolster and suitably secured thereto. One end of each plate 28 projects beyond the outer end of the bolster and is formed with an eye 30, and to this eye is pivotally attached a turnbuckle 32, having an eye 34 at its upper end. At its lower end the turnbuckle 32 is provided with a hook 36 which has a detachable connection through a link 38 with an eye bolt or the like 40 carried by one of the runners 10. In this manner a firm connection is established between each end of each of the bolsters and the frame of the boat, whereby the bolsters are securely yet removably clamped in position, and the turnbuckles 32 may be adjusted to 80 tighten up these connections after the hooks 36 have been engaged with the links 38.

On each of the bolsters 20, and near the outer ends thereof, are mounted standards 42 suitably spaced apart to provide room for placing between 95 them a wagon box or lumber or other substances comprising the load. The standards 42 are forked at their lower ends to embrace the bolsters and these forked ends are pivoted on bolts or pins 44 extending through the bolsters. The bolts or pins 100 44 may be provided with suitable securing means such as cotter pins 46, and the bolts or pins may be removed when it is desired to remove the standards from the bolsters.

Pivotedly secured at 48 to the upper end of each 105 standard 42 is a curved brace 50. The braces 50 are disposed on the outer sides of the standards 42 and their lower ends are adapted to be received in sockets 52 formed in the end portions of the bolsters and through the plates 30 thereof. The 110

braces 50 are provided near their lower ends with 5 collars 54 or are otherwise formed with shoulders which engage the plates 30 to limit movement of the braces 50 within the sockets 52. The braces, when their lower ends are mounted in the sockets 52, serve to hold the standards in upright supporting position so that they may confine between them a load which is supported by the bolsters 20.

10 Arranged along one or both of the side margins of the platform 14 of the boat are side sill members 56 which are beveled or inclined on their outer faces as indicated by the numeral 58 in Figure 6. The side sills 56 are not continuous lengthwise of the platform but are made in sections, one section at each side of the platform being in front of the foremost bolster 20, another section being between the two bolsters and still another section being rearwardly of the rearmost bolster.

15 It is the purpose of the sills 56 to provide low side walls for the platform 14 for convenience in transporting certain kinds of material, and also to form suitable supports for the discs 60 25 of a disc harrow or similar farm implement as illustrated in Figure 6. The sills thus function to support the discs above the surface of the platform 14 and to prevent them from cutting or injuring the platform and the fastenings therefor.

30 My improved farm boat is a convenient and efficient means for transporting loads of various kinds and is susceptible of being used in several different ways as indicated by the foregoing description. The bolsters may be removed and replaced at pleasure and may be used either with or without the standards 42. Furthermore the 35 particular construction of the bolster, with its novel securing means and its efficient type of removable standard, may be used on boats, sleds, stone boats or the like of various kinds in addition to the particular type of boat herein shown and described. As the upper surfaces of the bolsters are smooth and plane, a wagon box may be removed or replaced by lateral sliding movement, by removing one of the standards 42 and its brace.

35 I claim as my invention:—

1. In a farm boat, a bolster comprising a beam,

a standard pivotally secured to the beam, and a brace member pivotally secured to the upper portion of the standard, said member being curved and being formed with a substantially straight lower portion, said beam being provided with a vertically disposed socket to receive the straight end of the brace member when the standard is in upright position, said brace member being provided with a shoulder spaced from its lower end adapted to engage the beam to limit movement of the brace member within the socket.

80 2. In a farm boat, a bolster comprising a beam adapted to be mounted on the boat transversely thereof, transverse cleats countersunk in the lower face of the beam and adapted to engage the boat to prevent rocking of the bolster, and means to removably secure the bolster ends to the sides of the boat.

85 3. In a farm boat, a bolster comprising a beam adapted to be mounted on the boat transversely thereof, transverse cleats countersunk in the lower face of the beam and adapted to engage the boat to prevent rocking of the bolster, and means to removably secure the bolster ends to the sides of the boat, said means including turn- 90 100 buckles.

4. In a farm boat, a bolster comprising a beam adapted to be mounted on the boat transversely thereof, transverse cleats countersunk in the lower face of the beam and adapted to engage the boat to prevent rocking of the bolster, means to removably secure the bolster ends to the sides of the boat, and pins removably mounted through the bolsters adapted to engage in sockets in the upper surface of the boat to hold the bolster 105 110 against longitudinal and lateral movement.

5. A farm boat comprising spaced runners, a platform thereon, a bolster arranged transversely of the platform, means to prevent longitudinal and transverse movement of the bolster on the 115 platform, means to prevent rocking movement of the bolster, adjustable connections between the end portions of the bolster and the sides of the boat, standards pivotally mounted on the bolster, and braces pivotally secured to the standards, the 120 free ends of the braces being adapted to engage the bolster at points spaced from the standards.

WILLIAM W. JOHNSON.
